UNITED STATES PATENT OFFICE.

JOHN A. PRICE, OF SCRANTON, PENNSYLVANIA.

FURNACE-GRADE.

SPECIFICATION forming part of Letters Patent No. 276,876, dated May 1, 1883.

Application filed February 21, 1883. (No model.)

To all whom it may concern:

Be it known that I, JOHN A. PRICE, of Scranton, in the county of Lackawanna and State of Pennsylvania, have invented certain new and useful Improvements in Furnace-Grates; and I do hereby declare the following to be a full, clear, and exact description of the same, reference being had to the accompanying drawings, forming part of this specification, and to the figures and letters of reference marked thereon.

This invention relates to that class of furnace-grates in which a number of separate rocking sections serve normally to support the fire, and operate when rocked to agitate the fire and cause the clinkers and ashes to be withdrawn therefrom and dumped into the ash-pit below; and it consists in the novel construction and combinations of parts, which I will first describe, and then point out particularly in the claims at the end of this specification.

Referring to the accompanying drawings, Figure 1 represents a bottom plan view of a furnace-grate constructed in accordance with my invention, the various sections being arranged for operation in pairs. Fig. 2 is a longitudinal section of the same, taken on the line *xx* of Fig. 1. Fig. 3 is a longitudinal sectional view of a modification in which the sections are arranged for simultaneous operation in the same direction. Fig. 4 is a similar view of another modification, and Fig. 5 a view of a modified form of grate-bar; Fig. 6, a view showing gearing which may be employed to rock the sections, and Fig. 7 a view showing the manner of connecting the removable fire-bars.

Similar letters of reference in the several figures denote the same parts.

A indicates the frame of the grate, and *B B'* the several rocking sections arranged therein. Each rocking section *B* consists of a cross-bar, *b*, bearing a number of $\sim$ -shaped bars, *c*, arranged in planes at right angles to the bar *b*, and connected to said bar *b* by interlocking notches or recesses *r s* in the respective bars, as in Fig. 7, so as to be removable, and the end bars, *b*, of the sections are provided with journals *d*, having bearings within the frame *A*, as shown. From this construction of the sections it will be seen that the fuel in the furnace is supported entirely by the bars *c* and away from the cross-bars *b*, and that therefore

the said bars *b* are prevented from extreme heat, and the tendency of them to warp is greatly diminished. As shown in Figs. 1 and 2, the several sections are connected alternately to two rods, *F F*, arranged on opposite sides of the grate, and given reciprocating motion alternately in opposite directions by means of a vibrating T-shaped lever, *G*. When the lever *G* is turned in one direction, the sections are rocked and the edges *e* of each section, as they rise, cut into the material above and loosen it, and carry it into the pockets between the adjoining sections, of which the depending cross-bars *b* of said sections form a part. Then upon the reverse movement of the lever the material in the pockets is discharged, this operation being repeated each time the lever *G* is vibrated.

To insure closeness of the pockets and prevent wastage where fine fuel is employed, a plate, *h*, extending out laterally on each side of each of the bars *b*, preferably at substantially right angles thereto, is formed upon or attached to said bars. These plates are preferably made of grated or comb form, as shown in Fig. 1.

The several sections of the grate may be so connected as to be capable of simultaneous vibration in the same direction—as, for instance, by means of a rod, *D*, connected to the cross-bar *b* of each section and operated by a lever, *E*, as shown in Fig. 3. In this instance, also, the plates projecting laterally from the bottoms of the cross-bars serve to form part of the pockets between the several sections.

It will be observed that in Figs. 1, 2, and 3 the bars *c* of one section are of $\sim$ form, while the bars *c* of the next adjoining section are of $\sim$ form, and so on throughout the series, the bars of the alternate sections being of the same form. This arrangement, though it is desirable when the sections are arranged to be operated in pairs, need not be followed where all the sections are adapted to be rocked together in the same direction; but in the latter case the bars *c* of all the sections may be $\sim$ shaped, as shown in Fig. 4.

Instead of forming the journals for the sections upon the end bars, *c*, they may be formed upon the cross-bars *b*, near the lower edges, as shown in Fig. 5.

It is obvious that instead of giving motion

to the several sections by means of connecting-rods, as shown, the journals of the sections may be extended through the frame and provided with gears meshing into one another, so that when one section is rocked all will be rocked. Fig. 6 shows gears such as may be employed for this purpose.

My improvements are applicable to stoves as well as to furnaces.

10 The — form of the bars *c*, I do not claim herein, broadly, as the same is made the subject of claims in Letters Patent of the United States granted to William McClave and J. A. Price, April 16, 1878.

15 Grates constructed in accordance with my invention are very effective, inasmuch as they operate to rake and disturb the fire over its entire area, effectively eliminating all cinders and ashes therefrom, and maintaining a proper 20 draft.

Having thus described my invention, I claim as new—

1. The grate-sections having cross-bars, the fire-supporting bars, and the plate projecting laterally from the bottom of the cross-bars, 25 substantially as described.

2. The combination, with the rocking bars, each consisting of the —-shaped fire-supporting bars, the depending cross-bars, and the plates on the cross-bars, of means, substantially as described, for operating the sections in pairs, substantially as described. 30

3. The combination, with the rocking bar, of the —-shaped fire-supporting bars, each removably connected to the rocking bar, substantially in the manner described. 35

JOHN A. PRICE.
